United States Patent Office

Des. 213,481

Patented Mar. 4, 1968

213,481

APPLICATOR FOR HAIR SETTING PREPARATION OR SIMILAR ARTICLE

Robert F. Hubbell, Los Angeles, Calif., assignor to Dep
Corporation, Los Angeles, Calif., a corporation of California

Filed Jan. 18, 1968, Ser. No. 10,209

Term of patent 14 years

U.S. Cl. D86—10
Int. Cl. D28—03

FIG. 1.

FIG. 4.

FIG. 2.

FIG. 5.

FIG. 3.

FIG. 6.

FIG. 9.

FIG. 7.

FIG. 10.

FIG. 8.

FIG. 1 is a top plan view of an application for hair setting preparation or similar article, showing my new design;

FIG. 2 is a front elevational view thereof;

FIG. 3 is a bottom plan view thereof;

FIG. 4 is a side elevational view thereof as seen from the right side of FIG. 2;

FIG. 5 is a rear elevational view thereof;

FIG. 6 is a top plan view of a modified form of my design shown in FIG. 1;

FIG. 7 is a front elevational view thereof;

FIG. 8 is a bottom plan thereof;

FIG. 9 is a side elevational view thereof, as seen from the right side of FIG. 7; and

FIG. 10 is a rear elevational view thereof.

I claim:

The ornamental design for an applicator for hair setting preparation or similar article, as shown and described.
